UNITED STATES PATENT OFFICE.

BURR V. DEITZ, OF SLINGERLANDS, NEW YORK.

WIRELESS TELEGRAPHY.

1,189,070.

Specification of Letters Patent. Patented June 27, 1916.

Application filed May 6, 1914. Serial No. 836,587.

To all whom it may concern:

Be it known that I, BURR V. DEITZ, a citizen of the United States, residing at Slingerlands, in the county of Albany and 5 State of New York, have invented new and useful Improvements in Wireless Telegraphy, of which the following is a specification.

My present invention relates to improvements in the art of wireless telegraphy or radio-transmission and has for its object 10 to provide a system whereby two or more messages or signals can be transmitted from one aerial system or apparatus with relatively high efficiency and without interference between the messages or signals.

A further object of the invention is to provide apparatus for accomplishing this 15 result which is relatively simple and inexpensive in its construction and which is capable of operating with high efficiency.

To these and other ends, the invention consists in certain improvements, and combinations and arrangements of parts, all 20 as will be hereinafter more fully described, the novel features being pointed out particularly in the claims at the end of the specification.

In the accompanying drawings:—Figure 25 1 is a diagram of a multiplex wireless telegraph or radio-transmission system embodying the present invention; Fig. 2 is a front elevation of a rotary discharger and alternator adapted to be used in connection with 30 the present invention; Fig. 3 is a top plan view of the rotary discharger and alternator.

Similar parts are designated by the same reference characters in the several views.

40 I have found from experience that while the discharges of a radio-transmitter occur as frequently as five-hundred times a second, each single discharge occupies so small a part of a second that the discharges in 45 the aggregate consume only a small fraction of the time elapsing during transmission. According to the present invention, I utilize a part of the time heretofore unused and existing in the intervals between discharges 50 to transmit one or more additional dis-

tinguishable messages or signals by applying one or more additional transmitters which, according to the present invention, are used with the same aerial system, that is to say, a plurality of transmitters are 55 employed in connection with a single or common aerial system.

I have shown in the accompanying drawings and will hereinafter describe a system embodying the present invention which 60 comprises two transmitters operating with a single aerial system. It will be understood, however, that the invention is not restricted to the precise arrangement shown, as equivalent arrangements are contemplated, and also it will be understood that 65 the invention comprehends a multiplex system which may employ two or more transmitters operating with the same aerial system.

70 In the system shown in Fig. 1, A represents an aerial system, B represents what I term a "rotary alternator" which serves to bring the different transmitters alternately or successively into operative relation with 75 the system, C and C' represent condensers for the respective transmitters, D represents a dynamo or source of power to operate the system, a multi-phase alternating current dynamo being shown. I and X represent 80 inductance for one transmitter and a condenser for the other transmitter respectively, O and O' represent oscillation transformers for the respective transmitters, R represents a rotary discharger operative 85 in synchronism with the alternator B and co-operative with the pairs of spark plugs L—L and M—M, T and T' represent the primary or step-up transformers, K and K' represent the keys of the respective transmitters, G represents the ground for the system, and U represents a motor which, in the present instance, is used to operate the rotary discharger R and the rotary alternator B. H and J designate stationary 95 spark plugs for the rotary alternator.

The elements above described are connected with the necessary fuses and switches in the following way:—The aerial A is connected to one side of the rotary alternator 100

B, it being shown connected to the elongated contact A' which latter is positioned to operate with the plugs B' on the alternator. The stationary spark plug H of the rotary alternator is connected to the inductance I of the left-hand transmitter, this inductance being preferably adjustable in order that it may vary the wave lengths from this transmitter, and the stationary spark plug J of the rotary alternator is connected to a condenser X for the right-hand transmitter to vary the wave lengths for the right-hand transmitter in order to enable the receiving operators to easily distinguish between the multiple transmission of messages or signals from the different transmitters. The oscillation transformers O and O' are connected by a wire O³ to ground G and the oscillation transformers are also connected to the inductance I and condenser X respectively, as shown. The oscillation transformers are also connected to the condensers C and C' and to the secondaries of the transformers T and T', the stationary spark plugs L—L of the rotary discharger being connected to the oscillation transformer O', condenser C' and transformer T', as shown, and the stationary plugs M—M of the rotary discharger being connected to the oscillation transformer O, condenser C and transformer T, as shown. The primaries of the transformers T and T' are connected to the multi-phase alternating current dynamo or source of power by the wires T² and T³, and the keys K and K' are connected to the multi-phase alternating current dynamo D by the wires T⁴ and T⁵. While the ground leads from both transmitters are connected permanently to the ground, the aerial, according to the present invention, is rapidly brought into operative relation with one transmitter and rendered inoperative relatively to the other transmitter, and vice versa, whereby when a message is being sent from one transmitter, the circuit between the other transmitter and the aerial is broken. Therefore, the entire energy from each transmitter is alternately or successively sent from the aerial system without loss through a transmitter not at that moment in action. To this end, the spark plugs of the rotary alternator and the rotary discharger corresponding to the different transmitters are so related that, when the plugs M—M on the rotary discharger corresponding to the left-hand transmitter are in discharging position, the spark plug H of the rotary alternator corresponding to this same transmitter is also in discharging position, while at this same moment the spark plugs L—L of the rotary discharger corresponding to the right-hand transmitter and the spark plug J of the rotary alternator corresponding to this same transmitter occupy positions between the projections

on the discharger and alternator respectively and are therefore in non-discharge positions. The reverse action takes place on further rotation of the discharger and alternator whereby the right-hand transmitter is brought into action relatively to the aerial and the left-hand system is rendered inactive relatively to the aerial. 70

In the construction shown, the rotary discharger R and the rotary alternator B comprise disks which are mounted on but insulated from a single shaft V of a motor U, the motor being preferably interposed between the discharger and alternator and the whole being mounted upon a suitable insulating base W. The rotary discharger R embodies preferably a metallic disk which is rigidly fixed on a rubber or insulating bushing P which occupies a plane perpendicular to the axis of the shaft V, the outer face of the disk having plugs S projecting therefrom equidistantly and being in circumferential alignment, these plugs being relatively long radially but of narrow circumferential length. The stationary plugs or electrodes 80 L—L and M—M are preferably mounted on the insulating base W at the outer side of the disk of the rotary discharger and are positioned in immediate proximity to the path of the plugs S on the disk, whereby the plugs S pass and are alternately in discharging relation with the pairs of stationary plugs L—L and M—M respectively. The faces of the stationary plugs L—L and M—M present surfaces which are relatively long radially and are narrow circumferentially to the corresponding or similar surfaces of the plugs S on the rotary discharger disk, providing spark gaps between the stationary and revolving plugs which will insure accurately timed and sharp discharges of the sparks between the plugs. 90

The rotary alternator is constructed similarly to the rotary discharger, it embodying a metallic disk fixed on but insulated from the motor shaft V and having plugs B' projecting from the outer face thereof, these plugs being relatively long radially but narrow circumferentially, and the stationary plugs H and J are mounted on the insulating base W and present similar faces to the plugs B' on the alternator disk. 110

The adjustment of the stationary plugs is such that, during rotation of the discharger disk, the plugs M—M are opposite to a pair of plugs S—S on the discharger disk, and the plug H will be opposite to a plug on the rotary alternator disk, while in using two transmitters, as shown, the plugs L—L are midway between the plugs on the rotary discharger disk and the plug J of the rotary alternator will also be midway between the plugs on the rotary alternator disk. Synchronism is thus obtained between the rotary discharger and the rotary alternator, and 120 125 130

when a discharge takes place between one set of plugs, the other set of plugs is in non-discharge position.

The motor U, preferably an electric motor, is so arranged, by reason of the position of its armature relatively to the position of the rotary discharger and alternator disks, that, while the motor is running at its speed on one phase of the alternating current, the 10 motor brings the plugs leading from the transmitting condenser, which is driven by the same phase current, to sparking position and discharges that condenser immediately after such condenser has become charged to capacity and the current has ceased to flow from the transformer which charged that condenser, each condenser being discharged in a like manner. While the 15 spark takes place in one transmitter only at a time, the speed of the motor and the rotary discharger and alternator is such that the discharges in any transmitter are sufficiently rapid and frequent to produce a musical note which is the audible result of the operation of one transmitter, and this musical note may be interrupted at will by action of the key of the respective transmitter to form 20 signals or messages.

3. A system of radio-telegraphy comprising a plurality of independent transmitters embodying oscillation transformers variable independently to produce natural sympathetic vibrations of different wave lengths respectively, a single aerial common to said transmitters, a rotary discharger common to said transmitters, a rotary alternator, and means for continuously operating such alternator synchronously with said discharger to alternately render the transmitters operative 25 relatively to said aerial and to render the other transmitter or transmitters inoperative with respect thereto. 70

While, as stated, but two transmitters are shown, a third transmitter may be added by introducing two additional electrodes or spark plugs to the rotary discharger and one additional stationary spark plug to the alternator, rendering the discharger and alternator synchronous and timing the system so that no two transmitters act at one time, the time space or interval between the actions of the different transmitters being preferably equal, this being accomplished by suitably spacing the additional stationary spark 30 plugs or electrodes for the rotary discharger and alternator. In a similar way, additional transmitters may be added to the system and, in any case, a multiplex system 35 is produced which enables a plurality of signals or messages to be transmitted from the same aerial with efficiency and without interference between the signals or messages.

4. A system of radio-telegraphy comprising a plurality of independent transmitters embodying oscillation transformers for producing trains of waves of different lengths respectively, a single aerial common to said transmitters, a rotary discharger common to said transmitters, a rotary alternator interposed between the oscillation transformers and the aerial, and means for continuously 40 operating said alternator synchronously with the discharger to alternately render the transmitters operative relatively to the aerial and to render the other transmitter or transmitters inoperative with respect thereto. 80

5. A system of radio-telegraphy comprising a plurality of independent transmitters embodying oscillation transformers operative to produce natural sympathetic vibrations of different wave lengths respectively, a single aerial common to said transmitters, a rotary discharger common to said transmitters, a single rotary alternator interposed between the oscillation transformers and the aerial, and means for continuously operating such alternator synchronously with the discharger to alternately render the transmitters operative relatively to the aerial and to render the other transmitter or transmitters inoperative with respect thereto. 90

6. A system of radio-telegraphy comprising a plurality of independent transmitters embodying oscillation transformers variable independently to produce natural sympathetic vibrations of different wave lengths respectively, a single aerial common to and inductively coupled to said transmitters, a rotary discharger common to said trans- 100

7. A system of radio-telegraphy comprising a plurality of independent transmitters 110

mitters, a rotary alternator, and means for continuously operating the alternator synchronously with the discharger to alternately render the transmitters operative relatively to the aerial and to render the other transmitter or transmitters inoperative with respect thereto.

In testimony whereof I have hereunto set my hand in presence of two subscribing witnesses.
